IGNITER FOR GAS BURNERS

Oscar J. Leins, Milwaukee, Wis., assignor to Milwaukee Gas Specialty Company, Milwaukee, Wis., a corporation of Wisconsin

Application June 22, 1931, Serial No. 545,901

6 Claims. (Cl. 158—115)

This invention relates to igniters for gas burners and may be characterized as an improvement upon the subject matter illustrated and described in my copending applications Serial No. 448,603, filed April 30, 1930, and Serial No. 471,180, filed July 28, 1930.

The present invention has to do with means for guarding against the escape of unburned gas from the burner in the event that the flame is quenched by liquid boiling over the sides of a vessel placed over the burner, and relates particularly to improvements in the means for automatically reigniting the gas issuing from the burner in cases where the flame is extinguished as above pointed out.

The invention is illustrated in the accompanying drawing, in which:

Figure 1 is a fragmentary plan view of an arrangement embodying the present invention;

Figure 2 is a fragmentary side elevational view partially in section and taken on the line 2—2 of Figure 1;

Figure 3 is a fragmentary side elevational view showing a modified torch head or automatic re-igniter arrangement;

Figure 4 is a fragmentary view similar to Figure 2 showing the invention embodied in connection with a "flash" type of lighter; and

Figure 5 is a fragmentary view of a modified form of conduit for positioning over the torch head.

Referring first to Figures 1 and 2, the usual gas manifold is illustrated at 5, and the gas burner is illustrated at 6, this burner being fed from the manifold 5 by the usual feed pipe 7, to which air is admitted, in the usual way, at the end nearest the manifold. Gaseous fuel is fed into the pipe 7 by way of the nozzle pipe 8, from manifold 5, and the nozzle pipe 8 is provided with the usual gas cock 9.

The lighter designated generally at 10, is provided in appropriate proximity to the burner 6. Per se the lighter shown forms no part of the present invention, and it will therefore suffice, for the purpose of this description, to say that it comprises a tube 11 leading from the manifold 5 and terminating at its outer upturned end in a torch head 12 an appropriate distance from the burner 6. One burner is shown, but it is to be understood that gas ranges embody a number of burners, usually four, and that the torch head 12 may be disposed centrally between the burners. The torch head 12 is provided with a protecting hood 13 mounted thereover, and this hood has four openings 14, 14 in the circular side

wall, each in line with the respective burner on the range. A tube 15 leads from each opening 14 toward the respective burner, as illustrated, each of these tubes having a longitudinal slot 16 along the bottom for the entry of air. In the 5 illustrated embodiment the outer end of each tube 15 overlies, in use, an integral foot extension 18 on the burner 6, and in order to permit cleaning and removal of the burners the tubes 15 are formed of supplementary inner and outer tube 10 sections 15a and 15b. The inner relatively short tubes 15a have relatively fixed support on the hood 13, and the outer tube sections 15b are hinged at 20 to the tube sections 15a to be swung up out of and down into alignment with the 15 tubes 15a.

The torch head 12 has pilot flame openings 21 directed through the tubes 15 towards the respective burners 6, and in this embodiment the tube 11 is connected with the manifold 5 by a 20 coupling 22. The coupling 22 has a constant bypass, adjustable by the valve screw 23, by which arrangement a constant pilot light is maintained at the openings 21. In this particular embodiment the lighter is of the "gravity" type, but 25 it is to be understood that it may be of the "flash" type, as will hereinafter appear.

Extending from each burner 6 toward the respective adjacent tube 15 is a foot extension 18 formed integral with the respective adjacent 30 burner and in open communication with the interior of the burner at 25. The top of each foot extension 18 is offset downwardly at 26 to underlie the outer end of the respective adjacent tube 15, and the top of this downwardly offset portion of the foot extension carries the torch head 27 which extends upwardly into the respective tube 15, as illustrated. The torch head 27 has a hexagonal or other suitable tool receiving portion 28 and a depending nipple 29 threaded into 40 the top of the foot extension 18. A port 30 opens upwardly through the nipple part of the torch head and within the tube 15 the torch head has a pair of diametrically opposite ports 31 and 32, one directed toward the pilot flame at the ports 45 21 of the torch head 12, and the other directed toward the burner openings 33 in the top of the burner 6. In this particular embodiment when a burner 6 is to be ignited, the cock 9 associated with that burner is opened and gas enters the 50 burner ready to be ignited at the burner openings 33. Gas also passes freely into the foot extension 18 and to the torch head 27, issuing therefrom in both directions, one stream of gas from the port 31 toward and to the pilot flame 55

at the ports 21 and the other stream of gas through the port 32 toward and over the burner. The gas issuing from the torch head 27 toward the pilot torch head 12 is ignited by the pilot flame at the torch head 12 and the flame is conveyed back to the torch head and to the stream of gas issuing from the port 32, thus causing a flame to be projected over the burner 6 to ignite the gas issuing from the burner openings 33. The ports 31 and 32 in Figure 2 are shown as being disposed substantially coplanar with the ports 33 of the burner, so that a lighting flame projected from the port 32 will pass over the burner ports 33 in proximity thereto, to assure positive ignition of the burner. The gas issuing from the torch head 27 remains ignited so long as the gas cock 9 is open, and it will be clear that the initial projection of the flame from the torch head is due to the initial rush of gas into the burner 6 and before the pressure thereof is relieved by the issuance of gas through the burner openings 33. By the time the pressure is thus relieved, the gas issuing from the burner openings 33, or enough of them to light the others, is ignited and the flame at the torch head 27 then subsides to appropriate pilot proportions.

In the event that liquid, boiling over the sides of a vessel disposed over the burner, falls upon the burner and quenches the flame thereof, it does so by closing of the burner openings by the liquid and this closing of these openings increases the pressure within the burner. This increase in pressure causes the projection of the flame from the port 32 over the burner and when the filled burner openings become cleared by the evaporation of the liquid therein, the gas issuing therefrom is ignited by this temporarily projected flame. As such reignition takes place, the gas pressure within the burner is obviously gradually restored and, accordingly, the flame at 32 gradually recedes to resume appropriate pilot proportions. It is to be noted that the torch head 27 is protected by the tube 15 against quenching.

In the embodiment of Figure 3 the burner 6' instead of being provided with an integral foot extension as before, is provided with an elbow 36 threaded at 37 into the outer end or outer periphery of the burner and in communication with the interior thereof. The opposite end of the elbow 36 is vertically disposed and the nipple 29' of the torch head 27' is threaded into this end of the elbow 36. This elbow arrangement enables use of substantially the same torch head proper as is illustrated in Figure 2, and the operation is substantially the same as described in connection with the preceding embodiment. It should be noted, however, that the ports 31' and 32' in this embodiment are disposed slightly below the plane of the burner ports 33, since certain types of fuel gases are extremely buoyant and the flame issuing from a laterally extending port tends to rise. By disposing the ports in this position, the flame will pass directly over the burner ports, even if the outer portion thereof does rise slightly, thus insuring positive ignition of the burner.

The embodiment of Figure 4 is substantially the same as the embodiment of Figure 2 except that the torch head 27a is provided only with the port 32a directed toward the burner 6a. This is the "flash" type of igniter, in which the lighting flame from the torch head of the lighter is conveyed by a flash valve or the like, which may be provided at the coupling between the tube 11

and the manifold 5. The automatic reignition of the burner from the torch head 27a is obtained by projection of the flame from the port 32a substantially as in the preceding embodiment.

In the modification illustrated in Figure 5, a conduit or outer tube section is indicated at 40. This tube section 40 is adapted to fit over the torch head 41 in a manner similar to that described with reference to Figure 2. The portion of the tube section immediately above the torch head 41 is cutout as indicated at 42 and a ventilating dome is positioned over this cutout portion. The dome 43 has a projecting flange 44 formed at its lower surface which may be welded or otherwise suitably secured to the tube section 40. The ventilating dome is provided with a series of spaced vent holes 45, preferably located immediately below the flattened top portion of the dome. As the torch head 41 burns, the products of combustion are liable to choke up the tube section 40, unless there is draft means provided for removing them. The dome 43 acts as a flue, allowing the burned gases to escape and drawing in over the torch head a continuous supply of fresh air.

The invention is not to be limited to the precise details illustrated and described.

I claim:

1. In combination, a gas burner, a pilot torch head, a hood over said torch head, a port in said torch head directed toward said burner, said hood having an opening in line with said port, a tube extending from said hood from the opening therein toward said burner, a foot extension formed integral with the burner and offset downwardly to underlie the adjacent end of said tube and a second torch head mounted upon the top of the downwardly offset portion of said foot extension and terminating in said tube, said second torch head having port means and the foot extension on the burner being in open communication with the interior of the burner for supplying gas to said last port means at a pressure varying with the pressure within the burner.

2. In combination, a gas burner, a pilot torch head, a hood over said torch head, a port in said torch head directed toward said burner, said hood having an opening in line with said port, a tube extending from said hood from the opening therein toward said burner, a foot extension formed integral with the burner and offset downwardly beneath the top of said burner to underlie the adjacent end of said tube and a second torch head mounted upon the top of the downwardly offset portion of said foot extension and terminating in said tube, said second torch head having port means and the foot extension on the burner being in open communication with the interior of the burner for supplying gas to said last port means at a pressure varying with the pressure within the burner, said second torch head having a depending nipple opening into the top of the foot extension.

3. In combination, a gas burner having an integral lateral extension in the side wall thereof, said extension being disposed below the top plane of said burner, and a torch head having laterally opposed ports coplanar with the top of said burner mounted in the top of said extension and communicating through said extension with the interior of said burner.

4. In combination, a gas burner, a laterally spaced pilot torch head for maintaining a pilot flame, a tube supported entirely at said torch head and extending toward said burner, a lateral ex-

5 tension on said burner having the top thereof offset downwardly below the top of said burner and extending under said tube, and a second torch head carried on the top of said extension beneath said tube and fed from said burner, said second torch head having opposed ports within said tube directed toward said pilot flame and toward said burner.

5. In combination, a gas burner, a lighter tube 10 including a torch head spaced laterally of said burner for maintaining a pilot flame, an extension on said burner extending laterally thereof toward said torch head and having its top offset downwardly below the top of said burner, a relay pilot 15 means on said extension having an upwardly extending head portion provided with communicating ports directed toward said burner and toward said torch head, said pilot means being fed from said burner, and a tube open along its bottom and extending between said torch head and

said extension, said tube having an enlarged opening in its bottom over said extension to receive therein the head portion of said relay pilot means and having an open end directed toward said burner.

6. A gas burner of the class described comprising a burner portion and an integral feeder tube portion, a plurality of burner ports in the upper surface of said burner portion, an integral offset lateral extension on one side of said burner portion and having its top surface disposed below the plane of the top surface of said burner portion, said extension having free communication with the interior of said burner portion and being closed about its lateral surfaces, and a vertically 15 directed port in the top surface of said extension providing for passage of fuel from the interior of said burner portion outwardly therethrough.
